(57) **CLAIM**

The ornamental design for a plant tray dome, as shown and described.

DESCRIPTION

FIG. 1 is an upper, right, front perspective view of a plant tray dome, showing a first embodiment of the new design; FIG. 2 is a right side elevation view thereof, the left side elevation view being a mirror image thereof;

FIG. 3 is a front elevation view thereof;

FIG. 4 is a top plan view thereof;

FIG. 5 is an upper, right, front perspective view of a plant tray dome, showing a second embodiment of the new design;

FIG. 6 is a right side elevation view thereof, the left side elevation view being a mirror image thereof;

FIG. 7 is a front elevation view thereof;

FIG. 8 is a top plan view thereof;

FIG. 9 is an upper, right, front perspective view of a plant tray dome, showing a third embodiment of the new design;

FIG. 10 is a right side elevation view thereof, the left side elevation view being a mirror image thereof;

FIG. 11 is a front elevation view thereof; and,

FIG. 12 is a top plan view thereof.

The broken lines depict environmental subject matter only and form no part of the claimed design.
